UNITED STATES PATENT OFFICE.

MICHAEL JANKIEWITZ, OF MANISTEE, MICHIGAN.

DESIGN FOR A PICTURE-FRAME.

40,806.

Specification for Design.

Patented Aug. 2, 1910.

Application filed February 2, 1910. Serial No. 541,650. Term of patent 7 years.

To all whom it may concern:

Be it known that I, MICHAEL JANKIEWITZ, a subject of the Emperor of Germany, residing at Manistee, in the county of Manistee and State of Michigan, have invented a new, original, and ornamental Design for Picture-Frames, of which the following is a specification, reference being had to the accompanying drawing, forming a part thereof.

Figure 1 is a plan view of the picture frame, and Fig. 2 is a side elevation of the same.

I claim:

The ornamental design for a picture frame as shown.

MICHAEL JANKIEWITZ.
